SHANK-GRIP, SLIDABLE JAW WRENCH

Oswald M. Gross, Detroit, Mich.

Application May 28, 1953, Serial No. 358,085

2 Claims. (Cl. 81—151)

1

This invention relates to wrenches of the adjustable type, wherein a movable jaw is adjustable in relation to a fixed jaw to accommodate various sizes of work; and relates, more particularly, to such wrenches of the sliding jaw type as that described in my earlier United States Patent No. 2,509,637 wherein movement of the adjustable jaw is effected without the aid of threaded adjusting nuts or other equivalent operating mechanisms.

The present invention still further avoids the use of ratchet or rack means, with their limitations as to precise adjustment, for locking the movable jaw in positions of operative setting; and provides for a simple manually slidable mounting of the movable jaw on the head of the wrench in such manner that it may be readily moved by the thumb of the operator into and out of working position, although pressure of work against the gripping face of the said movable jaw will effect a binding abutment of the jaw member with opposed surfaces of the wrench head which will thereby effectively lock the movable jaw against outward movement from the fixed jaw as long as pressure of the work is maintained against said movable jaw.

Still further objects or advantages additional or subsidiary to the aforesaid objects, or resulting from the construction or operation of the invention as it may be carried into effect, will become apparent as the said invention is hereinafter further disclosed.

In carrying the said invention into effect, I may adopt the novel construction and arrangement of parts hereinafter described, by way of example, having reference to the accompanying drawings, in which:

Figure 1 is a side view of my improved sliding-jaw end wrench;

Figure 2 is an edge elevation of the wrench;

Figure 3 is a perspective detail view of the head portion of the wrench including the fixed jaw;

Figure 4 is an exploded perspective detail view of the movable sliding jaw, showing associated parts;

Figure 5 is a schematic diagram indicating lines of force, with the movable jaw member only being shown in section on a plane indicated by the line 5—5 in Figure 2 for the sake of clarity;

Figure 6 is a side view of a modified form of adjustable wrench, similar to Figure 1, the handle being shown in fragmentary form;

Figure 7 is a right side edge view of the arrangement of Figure 6;

2

Figure 8 is a similar edge view of the slidable jaw member removed from Figure 6;

Figure 9 is a side elevation of a further modified form of this device, the handle being shown in fragmentary form;

Figure 10 is an enlarged cross sectional view taken on a plane indicated by the line 10—10 in Figure 9;

Figure 11 is a right edge view of the arrangement of Figure 9;

Figure 12 is a perspective view of Figure 9; and

Figure 13 is a right edge view of slidable jaw member removed from Figure 9.

Similar characters of reference indicate similar parts of the several figures of the drawings.

Referring first to the arrangement shown in Figures 1 to 5, inclusive; 20 indicates the handle of an adjustable end wrench having a broadened head portion generally numbered 21 which terminates in a fixed jaw 22 as in the manner usual in this type of wrench.

23 indicates the outer end surface proper of the wrench head, which surface, for the purpose of this description, forms a 90° angle with the face of gripping surface of the fixed jaw 22.

The movable jaw 24 extends from a slidable jaw member 25 which is guided and interlocked with the broadened head 21 in the simple and unique manner about to be described, which ensures a very free and easy operation of the adjustable jaw to or away from a work-gripping position by mere thumb pressure of the operator on the said slidable jaw member 25.

The said movable jaw 24 overlaps the outer end surface 23 of the wrench head, but does not touch at any point along this line, as shown is indicated at reference number 19 in Figure 2.

The interlocking arrangement about to be described assures an automatic locking of the said slidable member 25 on the head 21 of the wrench in its work-gripping position when the jaws 22 and 24 are subjected to a spreading tendency by reactive pressure of the work thereon when the wrench is in use.

Referring now, more particularly, to the diagram Figure 5, it will be noted that the sliding jaw member 25 which overlaps the face of the wrench head 21, as clearly shown in Figures 2 and 4, is provided on its abutting surface with one or more, but preferably two, tongues 125 and 225 which normally loosely fit one or more into corresponding grooves 122 and 220, respectively, formed in the opposed face of the wrench head 21.

These grooves extend in a direction substantially parallel with the end surface 23 of the

said head, and are characterized by the fact that they both taper in width (toward a left hand direction, as indicated in Figure 1) whereby the spacing of the upper and lower walls of each of these grooves diminishes in a direction toward the gripping surface of the movable jaw 24.

This sliding jaw member 25 is provided on its abutting surface opposing the face of the wrench head 21 with tongues 125 and 225 normally loosely fitting into corresponding grooves 122 and 220, respectively, formed in the opposed face of the said wrench head 21, as clearly shown in the diagram, Figure 5.

While the spacing of the upper and lower walls of each of these grooves 122 and 220 increases in height in a direction away from the gripping or friction surfaces of the movable jaw 24, the upper and lower edges of the tongues 125 and 225 are parallel throughout almost their entire length.

It will be seen, from an examination of Figure 5, that movement of the jaw 24 away from the fixed jaw 22 to widen the opening between the jaws to receive work, will result in the upper and lower walls 31 and 28 (and 29 and 33) progressively encroaching on the upper and lower edges of the said tongues 125 and 225.

It should be understood that this angle of tapering on main body member 21 is actually very slight and, for satisfactory results in the operation of the device, it is intended that the taper of the upper and lower friction faces of each of the said grooves 122 and 220 shall not exceed an included angle of 0°-60°, so that the clearance at any time between the lower and upper edges of the tongues of 125 and 225 and the opposed abutment faces 28 and 31 of the groove 122 (and 33 and 29 of the groove 220) will not exceed that which will permit a rocking of the gripping face of the jaw 24 in excess of 2°, in the manner indicated by the broken line A in Figure 1.

It is intended that the rocking angle of the said jaw 24 shall also include that which is due to the normal flexing of the said jaw 24, when subjected to the maximum forces imposed thereon when the wrench is operated on work of the character which it is designed to cope with.

In the diagram, Figure 5, I have indicated a point at 34 which may be regarded as an assumed center about which the movable jaw member 25 rocks when subjected to the pressure of work against the gripping face of the jaw 24; so that it will follow that, when the movable jaw member is applied to the head of a bolt, nut or other such work, this rocking will result in the corresponding angular movement of the tongues 125 and 225 in their grooves so that diagonally opposite corners 36 and 26 of the tongue 125 (and 27 and 32 of the tongue 225) are brought into forceful contact with the surfaces 31 and 28 of the groove 122 and 29 and 33 of the groove 220.

To increase the area of such contact under these circumstances these particular corners of the said tongues are bevelled off to a very slight degree, as shown to an exaggerated degree by the short heavy lines at 36, 26, 27, and 32 in Figures 1 and 5 of the drawings.

The broad head 21 of the wrench is shown as being longitudinally slotted at 49 in the direction of jaw movement to receive a stud 41 passing freely therethrough and secured to member 25 by peening the end of stud 41 over a spring washer 42 located in the counterbore 18 whereby to provide a degree of pressure between opposed sur-

faces of the wrench head member 21 and jaw member 25 and thus maintain each member in definite relationship to accommodate various sizes of work and to prevent total or undesired separation of the two said members.

It should be noted that this stud is not a pivot and merely floats in the slot 49.

The operation of this wrench is extremely simple. To close the movable jaw 24 upon the flats of a nut, or upon other work, the pressure of the thumb is exerted on the outer edge of the movable member 25 (as at the point indicated by the letter B in Figure 1) while the handle of the wrench is held by the fingers and palm of the same hand, and, when the movable jaw contacts the work, continued by slight pressure of the thumb in the same direction results in a slight tilting of the said member and consequently of its tongues 125 and 225 into abutment with the upper and lower faces of the grooves 122 and 220. D is counterclockwise movement of the wrench handle and E is clockwise movement thereof as viewed in the drawing.

The pressure of this abutment is amplified by any pressure exerted on the gripper faces of the jaws 22 and 24 by the operator by the wrench in applying a clockwise or counter-clockwise turning effort to the work resulting in pressure at points 44 and 43 in the one case, and at points 45 and 46 in the other case.

It should also be noted as an important feature of the arrangement described that, while primarily the rocking of jaw member 25 upon the jaws being initially engaged with work will theoretically result in two initial points of pressure contact at, say, 26 and 27 upon the surfaces 23 and 29, of member 25, the result of flexing of the member 25 under final load is to emphasize a third contact between one or other of the tongues 125 or 225 at the point 30 or the point 32 against the opposed surface of the fixed wrench head as at 31 or 33.

Consequently, as spreading pressure is exerted against the gripping faces of the jaws 24 and 22, frictional resistance between the tongues and the face walls of the grooves is augmented to further resist any undesired spreading apart of the jaws of the wrench.

To close the movable jaw 24 toward the fixed jaw 22, it is merely necessary to press with the thumb at point B, Figure 1. Conversely, to open the jaws the thumb is pressed at the point C, Figure 1. In this way, abutment pressure between the tongues 125 and 225 and the opposed faces of the grooves 122 and 220 is readily relieved to permit adjustment of the jaw 24 relative to the fixed jaw 22.

As explained, the said jaw 24 will be firmly locked in operative position on the work by reactive pressure applied to the jaws resulting from operation of the handle of the wrench in the usual manner in either direction, even though the thumb is no longer exerting pressure upon the edge B jaw 24 but is being used to obtain a complete grip on the handle of the wrench.

Referring to modification shown in Figures 6 to 8 inclusive; this modified form of adjustable end wrench incorporates practically the same principles as shown in Figure 1. The principal departure therefrom is embodied in the fact that the main body member 48 carrying the fixed jaw 49 forms a housing for the movable member 50 carrying the jaw 51. This member 50 slides between tapered longitudinal dual grooves 52 and 53 formed in the member 48, and contacts lat-

eral wall faces 53 set on a 15° angle (as are the faces of the contact surfaces at 47 in Figures 2 and 3). The longitudinal tapering of these grooves 52 (Figure 7) increases in perpendicular height as grooves approach fixed jaw 49, as in the arrangement of Figures 1 and 5.

The member 50 has a bottom bearing contact 54 as shown in Figures 7 and 8, and also has contact with the inclined faces 53 at 55 when work is held between jaws 49 and 51. In the side view, Figure 6, shows jaw 51 as shown in broken lines in a forward position, tipped toward fixed jaw 49, to illustrate the tilting function of the jaw member 50.

The natural position of said jaw member 50 is resting with its contact surface 55 in abutting with groove wall face 53 and held in vertical position by a spring 56 bearing on the member at 57 and pressing the member 50 up and back so that its face is tilted as indicated by the dotted line F, in Figure 6. The said spring 56 includes one complete coil with its lower end turned up 58 and resting on bottom channel at 59 (Figure 7).

The true horizontal end face 60 of the member forms a 90° angle with face 17 of the fixed jaw 49, and the under surfaces 61 of the movable jaw 51 is longitudinally inclined and only contacts the face 60 when final pressure load is applied to the handle 62. The limit of travel of the jaw 51 and member 50 on the fixed head of the wrench is determined by the abutment 63.

The operation of this wrench is simple: to close the movable jaw 51 upon the work, the pressure of the thumb is exerted on the outer edge of the movable jaw at 51 while the handle of the wrench is held by the fingers and palm of the same hand, and, when the said movable jaw 51 contacts the work, it seats itself at F, whereupon the dual tongues 55 press against the upper abutments 53 on the member 48 and the lower tongue 54 presses against the dual walls 52. The handle of the wrench completes this operation, in the example, Figure 1. To open, it is only necessary to pull with the fingers on the movable jaw at 51.

Attention is now directed to the second modification shown in Figures 9 to 13, inclusive. In this arrangement a modified form of adjustable end wrench incorporating the principle of using one or more tapered grooves wherein a tongue on the movable jaw member initially binds between tapered groove walls upon working pressure being applied to the jaws of the wrench, and a third point of pressure brought into effect upon application of additional working pressure to the wrench handle to heighten the resistance to undesired separating motion of the jaws.

In this last example the movable jaw 64 extends from a movable saddle member 65 which is divided into two flange portions 66 and 68 between which the broadened head 68 of this wrench extends, as very clearly shown in Figure 12.

The flange 66 is provided with a tongue 166 (Figure 10) engaging in a corresponding transverse groove 167 formed in the wrench head 68, the upper and lower walls 69 and 70 respectively of this groove converging in the direction of the opening movement of the jaw 64 in the manner of the corresponding grooves referred to in the earlier examples described and illustrated.

It is preferred that these walls 69 and 70 be somewhat bevelled with respect to one another, as clearly shown in Figure 10, so that said groove 167 is somewhat of a dovetail form in cross-sec-

tion; and that the upper and lower edges of the tongue 166 be similarly bevelled to conform therewith, as will be obvious. 71 and 72 correspond to and operate in the manner of points of pressure contact 30 and 26 of Figure 5.

The flange member 83 has no tongue and its lower edge rides on a transversely extending shoulder 81.

In Figure 9, the dotted line 74 represents the 10 position of the face of the movable jaw when in gripping contact with the work (which is also the position occupied by the face of the movable jaw when normally at rest and rocked to that position by a compression spring 75 which is 15 housed in the lower end of the flange 66). This spring is provided with a wear-resisting button 76 which is constantly pressed against the lower face 70 of the groove 167.

The said movable saddle member 65 has an internal surface 78 extending between the two flanges, and slightly spaced from the upper edge 77 of the head 68, so that this surface 78 will 20 only come into contact with said edge 77 when pressure of the work on the movable jaw is sufficient to flex the saddle member to such an extent. The maximum travel of the jaw 64 and saddle member 65 is limited by suitably positioned abutment stops 80.

To close this wrench on the work, the movable 25 jaw is simply pressed with the thumb on the outer edge near the stop 80 while the handle 79 of the wrench is held by the fingers and palm of the same hand. This pressure tilts the movable jaw 64 so that its face assumes the position 30 shown in full lines at 73 in Figure 9, and, when the movable jaw contacts the work, it is again forced to the position indicated by the drift line 74 thus causing the upper face 71 of the tongue 166 to come into frictional abutment with the upper face 69 while the lower edge 72 of the flange 66 is rocked into frictional gripping engagement with lower face 70 of the groove 167. This gripping of the opposed faces secures the 35 movable jaw 64 in its working position against being disturbed when the handle of the wrench is operated in either of its directions.

It will be observed, from the foregoing examples, that my improved type of wrench is characterized by the movable jaw being carried 40 by a member transversely slidabale over the face of the head of the wrench (which carries the fixed jaw), the said member and the opposed face of the wrench head having interlocking tongue and groove guiding means in which the 45 upper and lower spacing of such tongue and groove arrangement is of a tapered nature becoming progressively restricted as the movable jaw is moved outwardly of the said fixed jaw; the interlocking of said wrench head and said movable member is further characterized by opposed surfaces coming into abutment at two separated points, upon a slight initial rocking of the movable jaw outwardly from the fixed jaw when the wrench is applied to work, with a third point of abutment occurring when additional rocking force is exerted against said movable jaw by additional applied pressure of the wrench to the work.

It should also be noted that, while in Figure 5, for example, both of the grooves 122 and 220 are shown as being tapered in form (this being a preferred arrangement), they need not necessarily be so as only one or other of these grooves 75 may be of a tapered nature and a reasonably

satisfactorily operating device obtained where a cheaper form of construction may be desired.

It should also be further noted, that I do not limit myself to utilizing the particular form of jaws illustrated in the drawings as these may be of any shape or character suitable to the gripping of the particular type of work which the wrench is intended to handle, or to suit the mode or direction in which the jaws of the wrench are to be applied to the work. Thus the jaws may be of a type intended to grip the work in an end-wise manner, instead of being laterally applied thereto, in which case, of course, the handle of the wrench might also be suitably offset or shaped to permit the application of the wrench to the work in that manner.

This invention may be developed within the scope of the following claims without departing from the essential features of the said invention, and it is desired that the specification and drawing be read as being merely illustrative of a practical embodiment of the same and not in strictly limiting sense.

What I claim is:

1. In an adjustable wrench having a fixed jaw and a slidable jaw, a wide head member carrying the fixed jaw, and a laterally movable member overlapping said head member and carrying said slidable jaw, said members having interlocking tongue-and-groove formations extending transversely of their abutting surfaces with the upper and lower edges of said formations spaced to permit slight rocking of the slidable jaw when operated against work to effect initial frictional locking contact between said formations at two points to resist further opening of said jaws when the wrench is operated against such work, said members being provided with

further spaced abutments spaced to further contact upon additional pressure of work applied to said movable jaw to an extent flexing said movable jaw member.

2. In an adjustable wrench having a fixed jaw and a slidable jaw, a wide head member carrying the fixed jaw, and a laterally movable member overlapping said head member and carrying said slidable jaw, said members having interlocking longitudinally tapered tongue-and-groove formations extending transversely of their abutting surfaces with the upper and lower edges of said formations spaced to permit slight rocking of the slidable jaw when operated against work to effect initial frictional locking contact between said formations at two points to resist further opening of said jaws when the wrench is operated against such work, said members being provided with further spaced abutments spaced to further contact upon additional pressure of work applied to said movable jaw to an extent flexing said movable jaw member.

OSWALD M. GROSS.
